UNITED STATES PATENT OFFICE.

SAMUEL D. STEEL, OF WOODLAWN, PENNSYLVANIA.

RAIL-CLAMP.

1,027,292.

Specification of Letters Patent. Patented May 21, 1912.

Application filed December 16, 1911. Serial No. 666,119.

To all whom it may concern:

Be it known that I, SAMUEL D. STEEL, a citizen of the United States, residing at Woodlawn, in the county of Beaver and State of Pennsylvania, have invented new and useful Improvements in Rail-Clamps, of which the following is a specification.

The present invention relates to clamps for rails.

10 In carrying out my invention it is my purpose to provide a clamp comprising a pair of elements arranged adjacent the opposite faces of the rails and contacting with the head of the rail as well as the base flanges. 15 thereof, the said clamps being secured together in an effective and novel manner which will prevent the displacement of the clamps even after the securing elements have been removed.

20 I also aim to provide a clamp of this character which may be secured to wooden, plastic or metallic rails, which comprises few parts and which will effectively sustain the rails against lateral or downward movement.

25 With the above objects and others of a similar nature in view, the invention resides in the novel construction, combination and arrangement of parts hereinafter fully described and claimed.

30 In the drawings, Figure 1 is an end elevation illustrating my improvement applied to a rail. Fig. 2 is a top plan view of the same. Fig. 3 is a sectional view upon the line 3—3 of Fig. 2. Fig. 4 is a perspective 35 view of one of the clamps. Fig. 5 is a top plan view of the plate. Fig. 6 is an elevation of the bolt. Fig. 7 is a top plan view of one of the locking blocks. Fig. 8 is an elevation of one of the retaining rings. Fig. 40 9 is a view of one of the pins. Fig. 10 is a transverse sectional view illustrating the application of my improvement upon the ordinary angular fish plates.

Referring now to the drawings in detail, 45 the numeral 1 designates a tie for railway rails. This tie may be constructed of plastic material, or wood or of iron, and the numeral 2 designates what I term a tie plate, which may be formed with or which may 50 be secured to the upper face of the tie 1 in any desired manner. The plate is centrally formed adjacent its opposite edges with spaced elongated slots 3 and the plate is further provided adjacent the walls formed 55 by the said slots 3, with depressions or openings 4.

The numeral 5 designates a bolt. This bolt comprises a horizontal body-portion 6 and annular arms 7. The body 6 is arranged below the plate 2, and the arms 7 project 60 through the elongated openings 3 thereof.

The numeral 8 designates the clamps. One of these clamps is arranged upon each of the opposite faces of each of the rails, but as all of the clamps are of similar construction a detailed description will be applied to only one, and the reference characters designating the portions of these clamps may be understood as equally applicable to the remaining clamps.

The clamps 8 comprise each a body portion 9, the same being formed of some suitable material preferably metal, and the inner faces of each of the body portions are undercut to provide the angular wall 10, 75 the same being of a shape conforming to the cross sectional contour of the base flange of the rail 11. The upper face of the base 9 is centrally provided with a rib 12, the inner face of which being vertically straight, 80 this rib extends entirely across the plate 8, and is centrally formed with an up-standing lug 13. The lug 13, has its inner face vertically straight and is adapted to engage with the web upon one of the faces 85 of the rail 11 while the top of the said lug is slightly inclined or beveled as at 14 so that the same will engage beneath the ball of the rail 11. The body 9 of the clamp 8 is centrally formed with an angular slot 15, 90 the said slot is adapted to receive the angular extending portions 7 of the bolt 5. The body portion 9 of the member 8 is also formed with openings 16, which are adapted to register with the openings 4 of the tie 95 plate 2, and communicating with these openings and arranged at the upper face of the body 9 are the enlarged recessed portions 17. The openings 16 and 3 are adapted to receive a shank 18 and a headed pin 19, and the head thereof is adapted to be received within the recess 17 so that the pin will remain flush with the top of the body portion 9 when inserted within the openings.

The numeral 20 designates the angular locking block. This block is provided with a central opening 21, which is adapted to permit of the block being passed over the extending arms 7 of the bolt 5. The block when properly positioned tightly engages 105 with the vertical face of the rib 12, and permits of the insertion of a nut 22 upon one 110

of the threaded extensions of the angular arm 7. Arranged between the nut 22 and the face of the locking block 20 is a spring washer 23, the latter adapted to exert pressure between the block and the nut to prevent accidental removal of the nut from the bolt due to the vibration incident to the rolling stock passing over the track 11.

It is here to be stated that the bolt 5 is 10 constructed of some bendable material and from the above description taken in connection with the accompanying drawings it will be readily noted that even should the nuts 22 be removed from the bolt the angular locking blocks, being retained upon the 15 angular arms of the bolt 5, will prevent the displacement of the parts and effectively sustain the rail upon the tie 1.

It will be further noted by reference to 20 figures of the drawings that the spring member 23 which I have termed a washer, is in reality more of a keeper when a pair of bolts 5 are employed as might be deemed necessary when the clamps are employed upon 25 T ties.

In Fig. 10 I have illustrated the device in connection with ordinary angular fish plates. These fish plates 26, are connected through the medium of the usual bolt 27 and the nut 28. The clamping elements are provided 30 with longitudinally extending upturned portions or beads 25, and the tie 29, in this instance is illustrated as hollow. The sustaining elements are substantially similar 35 to the device previously described.

Having thus described the invention what I claim is:—

1. In combination with a tie, of clamping members for the tie, each of said clamping members comprising a body having its inner 40 face undercut to correspond with the cross sectional contour of the base flange of the rail, each of said bodies being provided with rib, and centrally arranged integrally formed lugs for the body, said lugs engaging with the ball and web of the rail, a bolt carried by the tie, said bolt having oppositely disposed angular arms extending through the body of the clamp, wedge shaped locking blocks engaging the projecting portions of the bolt and adapted to contact with the ribs of the clamp, and nuts for the bolts.

2. In combination with a tie, of a rail upon the tie, a bolt member comprising a body and angular threaded ends, a clamp having angular openings and adapted to engage the angular portions of the bolt, said clamp having transversely arranged ribs, V-shaped locking blocks contacting the upper face of the tie, and the ribs, and a nut engaging the angular extensions of the bolt to compress the locking blocks against the ribs and against the clamp.

In testimony whereof I affix my signature 65 in presence of two witnesses.

SAMUEL D. STEEL.
